UNITED STATES PATENT OFFICE

104,860

DESIGN FOR A TEXTILE FABRIC

Walter F. Kaplan, San Francisco, Calif.

Application April 14, 1937, Serial No. 68,772

Term of patent 3½ years

To all whom it may concern:

Be it known that I, Walter F. Kaplan, a citizen of the United States, residing in the city and county of San Francisco, and State of California, have invented a new, original, and ornamental Design for a Textile Fabric, of which the following is a specification, reference being had to the accompanying drawing, forming a part thereof.

In the accompanying drawing:

The figure is a plan view of a textile fabric embodying my invention.

I claim:

The ornamental design for a textile fabric as shown.

WALTER F. KAPLAN.
